John W. Duty, Inventor

UNITED STATES PATENT OFFICE.

JOHN WALTER DUTY, OF BEARSVILLE, WEST VIRGINIA, ASSIGNOR OF
ONE-HALF TO JOHN W. GRIM, OF SAME PLACE.

CAR-COUPING.

SPECIFICATION forming part of Letters Patent No. 629,344, dated July 25, 1899.

Application filed March 17, 1899, Serial No. 709,482. (No model.)

To all whom it may concern:

Be it known that I, JOHN WALTER DUTY, a citizen of the United States, residing at Bearsville, in the county of Tyler and State of West Virginia, have invented a new and useful Car-Coupling, of which the following is a specification.

The invention relates to improvements in car-couplings.

10 The object of the present invention is to improve the construction of pin-and-link car-couplings and to provide a simple, inexpensive, and efficient device capable of coupling automatically when two cars come together and adapted to be readily uncoupled.

15 A further object of the invention is to provide a car-coupling of this character in which the parts may be readily arranged for coupling without necessitating a person going between cars and in which the link will be supported in position for guiding it into the mouth of the draw-head.

20 Another object of the invention is to provide means for supporting a pair of links adjacent to the mouth of a draw-head and to enable one of them to be readily swung into operative position from either side of a car, so that the parts may be quickly set for automatic coupling without danger to the operator.

25 The invention consists in the construction and novel combination and arrangement of parts hereinafter fully described, illustrated in the accompanying drawings, and pointed out in the claims hereto appended.

30 In the drawings, Figure 1 is a perspective view of a car-coupling constructed in accordance with this invention, the links being supported at opposite sides thereof. Fig. 2 is a 40 horizontal sectional view showing one of the links in position for use and the other secured to the side of the draw-head. Fig. 3 is a vertical longitudinal sectional view. Fig. 4 is a 45 detail perspective view of the spring-actuated pin-support.

Like numerals of reference designate corresponding parts in all the figures of the drawings.

1 designates a draw-head designed to be 50 mounted on a car in any suitable manner and having a spring-actuated pin-supporting de-

vice 2 sliding within it and consisting of an open frame of substantially rectangular form, the frame being slightly tapered, as shown, and having front and rear transverse portions. The frame of the spring-actuated pin-support is provided with a rearwardly-extending stem 3, guided in a suitable perforation or opening of the draw-head and having a coiled spring 4 disposed on it and interposed between the back of the open frame and the back of the draw-head, as clearly illustrated in Figs. 2 and 3 of the accompanying drawings. Within the frame is arranged a vertically-movable bar 5, provided with front and rear longitudinal ribs or flanges and having a recess 6 at its back to be engaged by the spring-actuated frame, whereby the bar is supported in an elevated position, and the front of the frame is adapted to be engaged by a link entering the draw-head, whereby the back of the frame will be carried out of the recess to cause the bar to fall and carry a coupling-pin 7 in engagement with the link 8. The draw-head is provided with a coupling-pin perforation 9, and it has a rear perforation or opening 10, conforming to the configuration of the flanged or ribbed bar 5. The bar 5 supports a horizontal bar 11, extending forward and rearward from the upper end of the said bar 5 and forming arms, the forwardly-extending arm being provided with a perforation for the reception of the coupling-pin. The horizontal bar 11 is provided with an eye and is designed to be connected with any suitable uncoupling mechanism; but as the vertically-movable bar extends entirely through the draw-head uncoupling mechanism may be arranged to lift the bar 5 from below. When the bar 5 is elevated, the pin is not only carried out of engagement with a link, but it is also set for automatic coupling.

In order to facilitate the coupling and to enable the draw-head to be quickly supplied with a link without necessitating the operator going between two cars, a pair of links 8 are provided, and they are supported at opposite sides of the draw-head, as clearly illustrated in Figs. 1 and 2 of the accompanying drawings, by curved bars 12, provided with slots 13 for the reception of the links and car-

rying vertical pins or fastening devices 14, which pass through the links. The mouth of the draw-head is enlarged at 15 to receive either of the curved bars, which are adapted to lie wholly in the said draw-head, as clearly shown in Figs. 2 and 3, and the inner ends of the curved bars 12 are reduced to form tongues 16, which are secured in slots or bifurcations 17 of the sides of the draw-head by vertical pivots 18. The links which extend through the slots of the curved bars project in advance and in rear of the same, and the rear or inner portion engages the spring-actuated frame when the curved bar is swung within the draw-head. This causes the coupling-pin to fall and engage the link, and when the pin is in engagement with the link the entire strain is borne by the coupling-pins and the said link, and the pivots of the curved bars and the pins 14 of the same are not subjected to any strain and do not require to be of extraordinary strength.

The draw-head is provided at opposite sides with hooks 19, arranged to engage the links, as illustrated in Fig. 2 of the drawings, whereby the link which is not in actual use is held against movement and is prevented from being swung around by the vibration of the draw-head. The curved arms which support the links in a horizontal position for guiding them into the mouth of a draw-head also support the links in position to be engaged by the hooks; but any other suitable fastening devices may be employed for securing the links to the sides of the draw-head.

The invention has the following advantages: The car-coupling, which is simple and comparatively inexpensive in construction, possesses great strength and durability, and it is positive, reliable, and automatic in its operation, and the links, which are arranged at opposite sides of the draw-head, are adapted to be swung into the same, so that the parts may be set for coupling from either side of a car without going between two cars. When one of the links is in use, the other is anchored or fastened to the adjacent side of the draw-head and is prevented from being thrown about by the vibration of the car-coupling. The draw-head, which is the same at the top and bottom, is adapted to be reversed, and it may be applied to a car in any suitable manner; also, any form of operating mechanism may be connected with the vertically-movable device which carries the coupling-pin, and such operating mechanism may be connected with either the top or bottom of the vertically-movable device.

Changes in the form, proportion, size, and the minor details of construction within the scope of the appended claims may be resorted

to without departing from the spirit or sacrificing any of the advantages of this invention.

What is claimed is—

1. In a car-coupling, the combination of a draw-head, an open substantially rectangular frame having front and rear transverse portions and slidingly mounted in the draw-head, a spring engaging the frame and adapted to move the same outward, a coupling-pin located in advance of the frame, and a vertically-movable pin-support comprising a bar passing through the draw-head and arranged to be engaged by the rear transverse portion of the frame, said bar being provided at its top with a forwardly-extending arm receiving the coupling-pin, substantially as described.
2. In a car-coupling, the combination of a draw-head, a coupling-pin, a link, and a horizontally-swinging support hinged to the draw-head at one side thereof and receiving the link and supporting the same in the same horizontal plane as the mouth of the draw-head, said link-support being adapted to carry the link into and out of the draw-head, substantially as described.
3. In a car-coupling, the combination of a draw-head, a link, and horizontally-swinging bar hinged to the draw-head at one side thereof, and provided with a slot receiving the link, said bar supporting the link in the same horizontal plane as the mouth of the draw-head and adapted to swing the link into and out of the same, substantially as described.
4. In a car-coupling, the combination of a draw-head, a pair of horizontally-swinging link-supports hinged to the draw-head at opposite sides thereof, and links mounted on the supports and arranged in the same horizontal plane as the mouth of the draw-head, either of the links being adapted to be swung into and out of the draw-head, substantially as described.
5. In a car-coupling, the combination of a draw-head, a pair of horizontally-swinging link-supports hinged to the draw-head at opposite sides thereof, links mounted on the supports and arranged in the same horizontal plane as the mouth of the draw-head, either of the links being adapted to be swung into and out of the same, and fastening devices mounted on the draw-head at opposite sides thereof and engaging the links, substantially as and for the purpose described.

In testimony that I claim the foregoing as my own I have hereto affixed my signature in the presence of two witnesses.

JOHN WALTER DUTY.
